UNITED STATES PATENT OFFICE.

ISAAC CHARLES DAKIN, OF WEST NEWTON, PENNSYLVANIA.

STEAM-BOILER FURNACE.

1,147,216.

Specification of Letters Patent.

Patented July 20, 1915.

Application filed April 7, 1914. Serial No. 830,197.

To all whom it may concern:

Be it known that I, ISAAC CHARLES DAKIN, a citizen of the United States, residing at West Newton, in the county of Westmoreland and State of Pennsylvania, have invented certain new and useful Improvements in Steam-Boiler Furnaces; and I do hereby declare the following to be a full, clear, and exact description of the invention, such as will enable others skilled in the art to which it appertains to make and use the same.

This invention relates to steam boiler furnaces, and has for its object to provide a furnace especially adapted for heating steam boilers, which shall be simple in construction, durable and efficient in use and an economizer in the matter of fuel.

With this and other objects in view, the invention consists in the novel construction and arrangement of parts as will be herein-after specifically described, claimed and illustrated in the accompanying drawing, in which,

Figure 1 represents a longitudinal sectional view through the furnace, showing the boiler in side elevation. Fig. 2 represents a vertical sectional view on the line 2--2 of Fig. 1.

Referring to the drawing in detail, the numeral 5 indicates the side walls of the furnace, the numerals 6 and 7 the rear and front walls respectively, and the numeral 8 indicates the supporting members disposed above the walls of the furnace and supporting the boiler 9. The front wall 7 of the furnace is formed with a suitable opening 10 and door closure 11 therefor for supplying fuel to the fire, and is further provided with the draft opening 12 having a door 13 communicating with the ashpit 14 above which are arranged the grate bars 15. The ends of the grate bars 15 are supported on a suitable ledge formed on the bridge wall 16 and a ledge formed upon the front wall 7, the ledges extending between the side walls 5 of the furnace. The bridge wall 16 is provided with a curved recess 17 in the upper edge thereof of greater radius than the radius of the boiler 9 and arranged in eccentric spaced relation to the wall of the boiler 9.

The lower portion of the boiler 9 or that portion inclosed within the walls of the furnace is provided with a plurality of integrally formed and radially extending flanges 18 provided with the apertures or perforations 19, the flanges being arranged on opposite sides of the bridge wall 16 and adapted to retard the heat and deflect the same against the sides of the boiler in its passage from the firepot 20 along the bottom of the boiler toward the opening 21 in the rear of the furnace for attaining the maximum degree of efficiency of the heat units of the products of combustion.

What I claim is:—

In a device of the class described, a furnace, a horizontally disposed boiler in said furnace, a bridge wall in said furnace having a substantially semicircular recess formed in the upper end thereof, the radius of said recess being greater than the radius of said boiler, said boiler being positioned within said recess with the center thereof below the center of said recess, whereby to provide a minimum space between the bottom of said boiler and said bridge wall, the remaining space therebetween increasing proportionately upward around the sides of said boiler, and a plurality of substantially semicircular and radially disposed flanges formed integrally with the exterior surface of the lower portion of said boiler at each side of said bridge wall, said flanges having a plurality of horizontally disposed apertures formed therethrough to provide for the more efficient heating of the flanges, said flanges coöperating with the recess of said bridge wall for retarding and directing the products of combustion against the bottom and around the sides of said boiler to thereby attain the maximum degree of efficiency of the heat units.

In testimony whereof I have signed my name to this specification in the presence of two subscribing witnesses.

ISAAC CHARLES DAKIN.

Witnesses:

A. M. DICK,
J. O. LANDSPARGER.
